US00D602464S

(12) **United States Design Patent**
Chung et al.

(10) **Patent No.:** US D602,464 S
(45) **Date of Patent:** ** Oct. 20, 2009

(54) **CELLULAR PHONE**

(75) Inventors: **In-Sik Chung**, Seoul (KR); **Hyun-Seop Kim**, Seoul (KR); **Chang-Hwan Hwang**, Goyang-si (KR)

(73) Assignee: **Samsung Electronics Co., Ltd.**, Suwon-si, Gyeonggi-do (KR)

(**) Term: **14 Years**

(21) Appl. No.: **29/333,249**

(22) Filed: **Mar. 5, 2009**

(51) **LOC (9) Cl.** 14-03

(52) **U.S. Cl.** ..... D14/138 AD

(58) **Field of Classification Search** ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3

See application file for complete search history.

(57) **CLAIM**

The ornamental design for a cellular phone, as shown and described.

DESCRIPTION

FIG. 1 is a perspective view of a cellular phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view of the cellular phone showing our new design in a state in which the cellular phone is open when used; and,

FIG. 9 is a right side elevational view of the cellular phone showing our new design in a state in which the cellular phone is open when used.

The broken lines immediately adjacent the shaded areas represent the bounds of the claimed design while all other broken lines are directed to environment and are for illustrative purposes only; the broken lines form no part of the claimed design.

1 Claim, 9 Drawing Sheets
